(57) **CLAIM**

The ornamental design for a can opener as shown and described.

DESCRIPTION

FIG. 1 is a top, rear perspective view of a can opener showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a bottom, front perspective view thereof;

FIG. 9 is an enlarged detail view taken from portion 9 of FIG. 1;

FIG. 10 is an enlarged detail view taken from portion 10 of FIG. 3;

FIG. 11 is an enlarged detail view taken from portion 10 of FIG. 3; and,

FIG. 12 is an enlarged detail view taken from portion 12 of FIG. 4.

The broken lines in the drawings indicate enlarged portions which form no part of the claimed design.

1 Claim, 12 Drawing Sheets
